UNITED STATES PATENT OFFICE

163,370

LAMP

Joseph R. Casper, Baltimore, Md.

Application January 18, 1951, Serial No. 13,859

Term of patent 7 years

(Cl. D48—20)

To all whom it may concern:

Be it known that I, Joseph R. Casper, a citizen of the United States, residing in the city of Baltimore, State of Maryland, have invented a new, original, and ornamental Design for Lamps, of which the following is a specification, reference being had to the accompanying drawing, forming part hereof, and in which:

I claim:

The ornamental design for a lamp, as shown.

JOSEPH R. CASPER.
